UNITED STATES PATENT OFFICE

ROY B. WEIMER, OF AKRON, OHIO, ASSIGNOR OF ONE-HALF TO THE MILLER RUBBER COMPANY, OF AKRON, OHIO

TOY

Application filed January 27, 1928. Serial No. 249,890.

This invention relates to improvements in children's toys of the type embodying a body of inflatable elastic material such as rubber capable of inflation, and aims to provide a simple and inexpensive article where in such inflatable body is combined with a rigid structure of sheet material capable of forming, with the inflatable article, a novel and amusing form of toy which may be embodied in various interesting forms.

The invention includes the novel construction hereinafter described and defined by the appended claims.

In the accompanying drawings two embodiments of the invention are shown by way of example but it will be readily appreciated that both the enclosing or frame structure and the inflatable body could be modified in many ways according to the type of toy desired.

On these drawings:

Fig. 1, is a side view drawing showing the invention embodied in a toy animal.

Fig. 2, is a vertical section.

Fig. 3, is a plan view of the blank from which the cardboard structure is made.

Fig. 4 is a plan of the rubber animal before doubling over.

Fig. 5 is a plan view showing the invention embodied in a toy airship.

Fig. 6 is a side elevation thereof.

Fig. 7 is a view of the cardboard blank.

Fig. 8 and Fig. 9 are views of the propeller and rudder respectively.

Referring by reference characters to these drawings and first to the form shown in Figures 1 to 4, the numeral 1 designates a structure of relatively rigid material such as cardboard of substantially box-like form, capable of being made from a single blank such as shown in Figure 3, cut to the proper shape and scored, to permit folding into box-like form. 2, designates a body of inflatable material such as elastic sheet rubber commonly used for making inflatable toys, which in this instance is shown in the form of a toy animal having the appearance of a dog (though of course it could be made to simulate any other animal) being provided with customary means for inflation at one point as for ex-

ample at the extremity of one of the legs as indicated at 2^a.

The cardboard structure is provided with openings through which the head, tail and legs project, the said parts being readily insertible through these openings before the body is inflated. When so inserted and with the parts of the structure folded to proper position and secured, as by pasting together the marginal edges 2^b and 2^c and interlocking the parts 2^a and 2^b by the tongue and slot connections *d* and *e* inflation of the body 1 will cause expansion thereof, on both sides of the respective openings, producing an inter-locking connection between the body and cardboard structure.

In the form shown in Figs. 5 to 9 inclusive, the toy takes the form of an airship provided with a cardboard structure 3, which forms the main body thereof, (wings, etc.) and 4 the inflatable body which projects at front and rear thereof, through openings 3^a and 3^b, and is preferably of substantially cigar shape. At one end is located a cardboard piece cut to simulate a propeller as indicated at 5 and 75 having an opening through which the corresponding contracted end of the body is inserted and with which is it interlocked by expansion.

At the other end is provided a cardboard article 6, to simulate a rudder member or analogous device, which comprises a single sheet having parts bent at an angle to each other and each provided with openings through which said opposite end of the body projects.

A toy as above described presents a very amusing appearance, is capable of being very economically manufactured, and can be packed flat for shipment. The several parts 90 can be readily printed or colored to give any desired effects.

Having thus described the invention, what is claimed as new is:

1. A child's toy comprising a single sheet 95 of thin stiff cardboard or the like relatively stiff, nonyielding material folded to form a box-like structure providing an enclosed space, said box-like structure having relatively thin walls disposed in different planes 100

and provided with openings punched through the walls, and a body of inflatable expansible material disposed within the enclosed space and having parts projecting through said 5 openings substantially perpendicularly with respect to said walls and interlocked therewith, by the expansion of said body on either side of the relatively sharp edges presented by the walls at said openings to a diameter or 10 width exceeding the diameter or width of said openings.

2. A child's toy comprising a box-like structure of relatively thin stiff inextensible sheet material having openings punched 15 through its bottom and through its two end walls, and an expansible quadruped figure of expansible material having a body portion within said structure, and head, leg, and tail forming portions extending through said 20 openings and expanded on either side of the relatively sharp edges presented by the walls at said openings to a diameter or width exceeding the diameter or width of the openings to provide an interlocking connection there- 25 with.

In testimony whereof, I affix my signature.
ROY B. WEIMER.
